UNITED STATES PATENT OFFICE.

GEORGE SKINNER, OF CLEVELAND, OHIO.

SIGNAL-LANTERN.

SPECIFICATION forming part of Letters Patent No. 223,548, dated January 13, 1880.

Application filed November 20, 1879.

To all whom it may concern:

Be it known that I, GEORGE SKINNER, of Cleveland, in the county of Cuyahoga and State of Ohio, have invented certain Improvements in Railway-Signal Lanterns, which improvements are fully set forth in the following specification and accompanying drawings, in which—

Figure 1 is a perspective view of a lantern 10 with a portion of case broken out to show interior construction. Fig. 2 is a vertical section. Fig. 3 is a detached view of one of the flags.

The object of this invention is to enable the 15 operator to see that the flag is down without the necessity of going out and looking at the broad side of the lantern containing the windows.

The invention consists in providing the narrow side of the lantern, facing toward the building 20 in which the operator is located, with windows, and also providing the flags with side wings, which, when the flags are down, bring said wings opposite to said windows, whereby 25 the operator is enabled to see whether the flags are lowered or raised by looking through the narrow side windows of the lantern.

In the drawings, A represents the case of the lantern, containing the lamp and the 30 working parts. The case is provided with two doors, B B', on each of its broad sides, the lower doors, B, having transparent-glass panels, and in one narrow side of the case two narrow glass windows, C C, are provided below.

On the inside surface of the narrow sides 35 of the case are made grooves or ways *d d*, near to the doors B B', in which the frames of flags D D slide, being operated by cords E E, attached to their upper edge and passing over 40 pulleys F and G in the top part of the frame, and extending to and into a building or office, where the operator can operate and control

them. Said flags consist of light frames covered with a red-colored partially-transparent material, which, when brought down before the lamp, causes a colored light to appear through the aforesaid glass door-panels. To one side of said flag-frames are attached by suitable means narrow wings H H, of similar material as the flags, which are carried up and down with the flags whenever they are moved, and, when down, cover the inside of the narrow windows C C.

It will be seen from the foregoing that 55 when the flags are lowered the wings on their sides display their surfaces through the narrow side windows, C C, which are facing toward the building or office of the operator, and thus indicate that they (the flags) are down, as 60 desired. The broad sides of the lantern, facing up and down the railroad-track, are out of view to the operator, who would be obliged, without the use of the said side windows, C C, and the side wings, H H, to go outside to assure himself that the flags had moved as he desired, which, in some instances, would be very inconvenient, as the office might be located some distance from the lantern.

This device is not confined to night-service 70 alone, but is equally adapted to day-service, as the partition which divides the lantern centrally shows a white surface by either lamp-light or daylight.

Having described my invention, I claim— 75
In railway-signal lanterns having the flags D D arranged to be operated by means of the cords E E, passing over the pulleys F G, the combination, with said flags, of the wings H H, for indicating the position of the flags 80 through the narrow side windows, C C, substantially as and for the purpose specified.

GEO. SKINNER.
